UNITED STATES PATENT OFFICE.

WARREN B. HOWE AND FRANK B. DAVIDSON, OF CHICAGO, ILLINOIS.

BOX.

SPECIFICATION forming part of Letters Patent No. 482,479, dated September 13, 1892.

Application filed January 22, 1891. Serial No. 378,686. (No model.)

To all whom it may concern:

Be it known that we, WARREN B. HOWE and FRANK B. DAVIDSON, of Chicago, in the county of Cook and State of Illinois, have 5 invented certain new and useful Improvements in Paper Boxes; and we do hereby declare that the following is a full, clear, and exact description thereof, reference being had to the accompanying drawings, and to the letters of reference marked thereon, which form a part of this specification.

This invention relates to an improvement in the construction of a paper box of that class having connected side walls and flaps at one 15 or both ends, which are adapted to be folded together and interlocked to form the end wall or walls of the box.

The invention consists in the matters hereinafter described, and pointed out in the appended claims.

In the accompanying drawings, illustrating my invention, Figure 1 is a perspective view of one end of a box embodying our invention, illustrating a somewhat-different construction 25 in the form of the end flaps. Fig. 2 is a similar view showing the same box with the end flaps partially unfolded. Fig. 3 is a plan view of one end or edge of the blank used for forming the box shown in Figs. 1 and 2. Fig. 4 is 30 a perspective view of one end of a box, which differs slightly from that shown in Figs. 1 and 2. Fig. 5 is a similar view of the box shown in Fig. 4, with the end flaps partially unfolded.

In Figs. 1 and 2 we have shown one end of a 35 box having only one set of interlocking flaps, the side walls of the box shown in this instance being longer in one direction than the other and the interlocking flaps being applied to the longer side walls.

40 D D² are flaps belonging to the shorter sides of the box, while D' D³ are flaps belonging to the longer sides thereof. The flap D' is of rectangular shape with a straight free edge, while the flap D³ is provided with trans- 45 verse notches or slits, forming two lateral pro- jections d d and an intermediate tongue d', which tongue is made shorter than the pro- jections d d for convenience of folding the parts together. The flap D' is provided with 50 U-shaped cuts or slits d² d², forming tongues d³ d³, said tongues being arranged laterally or with their free ends parallel with the sides of

the main flap D'. The slits d² d² are so located that the side margins of the tongue d' may be inserted beneath said lateral tongues 55 when the flaps D' and D³ are interlocked. The ends of the flaps D D² are tapered or otherwise made sufficiently narrow or are provided with narrow projections to also enter the slits d² d². The flaps D' D³ are folded together or interlocked in the same manner as the similar flaps hereinbefore described, except that the tongue d' is preferably, but not necessarily, introduced between the tongues d³ d³ and the body of the flap D', and the 60 flaps D D² are bent over the said flaps D' and D³ and the ends thereof inserted in the slits d² d², which latter are placed so close together as to be exposed between the parts d d of the flap D³, as clearly shown in Fig. 1. 65 The engagement of the tongue d' with the lateral tongues d³ d³ makes the end of the box stiffer or stronger to resist inward pressure, because the said tongues d³ d³ hold the free end of the tongue d' from being bent or de- 70 flected inwardly away from the flap D', as it would tend to do when the flaps were pressed inwardly if not so interlocked with said tongues d³ d³. The engagement of the ends of the flaps D D² with the slits d² d² obviously 75 secures the several flaps, so that no other fastening device is necessary. When it is de- 80 sired to hold the outer flaps D D² closed without affording any additional engagement of the tongue d' with the flap D', the slits d² d² 85 may be made straight instead of U-shaped and the ends of the flaps D D² inserted there- 90 in, with the same result as far as the secur- ing of the said outer flaps is concerned. It will 95 be understood, however, that the box having flaps made as described, may and commonly will be covered by a paper wrap- per when employed for packing merchandise, such as starch or dry-food products, which are liable to sift through the joints of the folded flaps.

Fig. 3 shows one end of the blank employed in forming the box shown in Fig. 5, said blank being provided with transverse slits d⁴ d⁴, forming the several flaps, and with an end 100 flap d⁵, like the similar blank hereinbefore described.

In Figs. 4 and 5 we have shown one end of a box similar to that shown in Fig. 5, with

the exception that the tongue d' of the flap D^3 is provided with two slits $d^6 d^6$, which are approximately parallel with the free edge of the flap, so as to form two lateral tongties 5 $d^7 d^7$. The said slits $d^6 d^6$ terminate at their inner ends a distance apart about equal to the space between the slits $d^2 d^2$, so that when the flap D^3 is engaged with the flap D' , with the tongue d' beneath said flap D^3 , the lateral tongties $d^7 d^7$ may be inserted through the said slits $d^2 d^2$. When the parts are thus constructed, the insertion of the said tongties $d^7 d^7$ through the slits $d^2 d^2$ serves to interlock the flaps $D' D^3$ with each other, so that they 10 cannot be pulled apart or will not become separated by accident or by the pressure of the goods within the box, and cannot be disconnected without first disengaging said tongties from the slits. In closing the end of the box 15 constructed as last described the ends of the flaps $D D^2$, which are made narrow for the purpose, are tucked into the slits $d^2 d^2$, preferably beneath the tongties $d^7 d^7$, as clearly seen in Fig. 4.

25 It will of course be understood that the novel features of construction herein shown, by which the opposite flaps of a box may be interlocked in the manner described, may be applied to either one or both pairs of flaps 30 at one end of a box, or to one or both flaps at both ends thereof, as desired. It is further obvious that as far as the construction of the flaps themselves is concerned the side walls or body of the box may be constructed in any 35 manner found convenient or desirable, and the use of a single blank such as is herein illustrated is not essential.

While the invention is herein described as applied to a box made entirely of paper or 40 strawboard, having permanently-connected side walls and adapted for shipment in "knockdown" form, it will of course be understood that the invention may be employed as well in connection with wrappers, pack- 45 ages, or cartons of other forms. Furthermore, it is obvious that as far as the construction of the interlocking flaps is concerned the body of the box or carton may be wholly or partially of other material than paper or 50 strawboard.

We claim as our invention—

1. A box provided with two flaps connected with opposite side walls of the box, one of said flaps being provided with two slits or notches extending inwardly from its outer 55 end to form a tongue and the other with two **U**-shaped slits forming interior tongties to engage with the side margins of the tongue upon the flap first mentioned when the flaps are folded together, substantially as described. 60

2. A box provided with two flaps connected with opposite side walls of the box, one of said flaps being provided with two slits or notches extending inwardly from its free edge to form a tongue, which tongue is slotted at each side 55 to form lateral tongties, and the other with two slits in its central part, which form tongties to engage with the tongue upon the flap first mentioned and which are adapted to receive the said lateral tongties for locking 70 the flaps together, substantially as described.

3. A box provided with four flaps connected with its side walls, one of said flaps being provided with slits or notches extending inwardly from its free edge to form a tongue, 75 the flap opposite thereto being provided with interior cuts or slits and the intermediate flaps being provided with narrow ends or projections adapted to enter said interior slits, substantially as described. 80

4. A box provided with four flaps connected with its side walls, one of said flaps being provided with slits or notches extending inwardly from its free edge to form a tongue, which tongue is slotted to form lateral tongties, the 85 flap opposite thereto being provided with interior cuts or slits adapted to receive the said lateral tongties and the two intermediate flaps being provided with narrow ends or projections adapted for insertion in said interior 90 cuts or slits, substantially as described.

In testimony that we claim the foregoing as our invention we affix our signatures in presence of two witnesses.

WARREN B. HOWE.
FRANK B. DAVIDSON.
